Des. 186,320

Patented Oct. 13, 1959

186,320

CHARCOAL BRIQUET PACK OR THE LIKE

Frank H. Mustin, Lansdowne, Pa., assignor to Frank H. Fleer Corporation, Philadelphia, Pa., a corporation of Delaware

Application November 25, 1957, Serial No. 48,630

Term of patent 14 years

(Cl. D32—1)

Fig. 1

Fig. 2

Fig. 1 is a top plan view of a charcoal briquet pack, showing my new design;

Fig. 2 is a front elevational view thereof; and

Fig. 3 is an enlarged perspective view thereof as seen from the top.

The bottom of the pack is plain.

I claim:

The ornamental design for a charcoal briquet pack or the like, substantially as shown and described.
